The ornamental design for a coating film transfer tool.

DESCRIPTION

FIG. 1 is a perspective view of the coating film transfer tool; FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a sectional view thereof along line 8-8 of FIG. 2; and,

FIG. 9 is a sectional view thereof along line 9-9 of FIG. 2.
